Inventor
John Briggs

UNITED STATES PATENT OFFICE.

JOHN BRIGGS, OF LOUISVILLE, KENTUCKY.

IMPROVED APPARATUS FOR CONDENSING STEAM AND ELEVATING FEED-WATER.

Specification forming part of Letters Patent No. 40,392, dated October 27, 1863; antedated October 20, 1863.

To all whom it may concern:

Be it known that I, JOHN BRIGGS, of Louisville, in the county of Jefferson and State of Kentucky, have invented a new and Improved Apparatus for Condensing Steam and Elevating Feed-Water for Steam-Boilers; and I do hereby declare the following to be a full and exact description of the same, reference being had to the accompanying drawings, making a part of this specification, in which—

Figure 1 is a vertical section of the said apparatus at *xx*, Fig. 2. Fig. 2 is a top view of the same, with a small part of the shell broken away to expose the interior.

Similar letters of reference indicate corresponding parts in both views.

The subject of my said invention is an apparatus in which water is elevated by the force of exhaust-steam and the steam afterward condensed by contact with the said water within a suitable reservoir, where the water may be retained for the supply of the boiler.

In order that others skilled in the art to which my invention appertains may be enabled to fully understand and use the same, I will proceed to describe its construction and operation.

A may represent the bottom of a vessel or other structure on or in which the apparatus is to be used.

B represents a steam cylinder; *C*, the valve; *D*, the steam supply pipe, and *E* the exhaust-pipe. The latter is formed at its upper part with an enlarged chamber, *E'*, and delivers into a reservoir, *F*.

G is a pipe projecting downward into the water in which the ship floats, or into any other suitable body of water. The said pipe is guarded near its lower end by a valve, *H*, permitting the upward flow of water, but preventing its descent. The upper end of the pipe *G* enters the chamber *E'*, and is there deflected away from the steam-cylinder or in the direction of the flow of exhaust-steam, as shown at *G'*.

I is a cup projecting upward from the pipe *G* in such a position that any water poured into it will flow into the lower part of the pipe.

J is a cock to open or close this external communication with the pipe *G*.

K is a pipe through which water may be taken from the reservoir *F* to supply the boiler.

L is a check-valve guarding a port in the top of the reservoir *F*, through which port any steam not already condensed may be allowed to escape to a second condenser of this or any other form.

To charge the apparatus the pipe *G* is first filled with water through the cup *I* and cock *J*.

The apparatus is then operated in the following manner: The exhaust-steam, flowing forward through the pipe *E* around the mouth of the pipe *G*, forces the air from the latter, producing a partial vacuum and causing the external water to be forced up the pipe *G* by atmospheric pressure, mingled with the steam and precipitated in a shower within the reservoir *F*, the water in turn effecting the condensation of the steam. The water on leaving the mouth of the pipe *G* strikes the elbow of the pipe *E*, which scatters and mingles it among the steam and renders the condensing action more complete.

An apparatus of the above description will elevate water twenty-five feet without expenditure of powder, the force of the engine being rather increased by the condensation of the steam, and the water thus elevated is in the act of condensing the steam heated preparatory to its introduction to the boiler. The reservoir *F* should, if practicable, be placed not more than twenty feet above the surface of the water. If the height to which the water is to be raised exceeds twenty-five feet, it should be done at two or more operations.

Having thus described my invention, what I claim as new therein, and desire to secure by Letters Patent, is—

The deflected water-pipe *G'* and steam-pipe *E*, when combined with the exhaust-port of a steam-engine, in the manner and for the purposes herein specified.

Witnesses: JOHN BRIGGS.
